UNITED STATES PATENT OFFICE.

EDWIN J. OYEN, OF BUFFALO, NEW YORK.

HANGER FOR CLOTHESLINES AND THE LIKE.

Application filed March 16, 1928. Serial No. 262,203.

This invention relates to a hanger which has been designed more particularly for facilitating the hanging of clothes in attics, cellars and similar places.

5 Its principal object is the provision of a simple and inexpensive hanger by which clothes lines can be conveniently and readily hung in limited spaces with a maximum carrying capacity and without danger of

10 sagging.

Other objects of the invention are to provide a hanger of this character which is easy to install and does not require the use of nails or like fastenings, which embodies 15 reliable means for securely anchoring the clothes line thereto without the use of knots, and which enables the clothes line to be readily attached to and detached from the hanger.

20 In the accompanying drawings:—

Figure 1 is a longitudinal section of the ceiling of a cellar showing my improved hangers and clothes line suspended therefrom. Figure 2 is an enlarged face or front 25 view of one of the hangers. Figure 3 is a transverse vertical section on line 3—3, Figure 2.

Similar characters of reference indicate corresponding parts throughout the several 30 views.

By way of example, my invention has been shown as applied to the ceiling of a cellar, 10 indicating the joists, 11 the flooring, and 12 the clothes line held firmly and securely 35 without sagging by the novel hangers 13.

Each hanger is constructed from a single length of resilient material, preferably galvanized wire, bent above midway of its length into U-shape. The resulting legs 14, 40 14 form the suspension or attaching arms of the hanger and their upper or free ends are laterally bent to provide anchoring spurs or prongs 15 for securely fastening the hanger to the joists. The attaching arms 45 may be of different lengths, if desired, to bring the prongs at different points in the grain of the wood-joist and avoid splitting it when securing the hanger in place with a hammer or like tool.

50 At its lower or bent end where the clothes line is engaged therewith, the hanger is provided with a gripping device for detachably securing the line thereto, the preferred form of device being shown in the drawings and 55 consisting of a coil 16 of one or more turns,

the adjoining turns of the coil normally lying in contacting engagement to provide yieldable jaws between which the clothes line is firmly pinched or anchored, as shown in Figure 3. The provision of this coil also 60 enables the legs 14, 14 to be spread or contracted when desired, as when obliged to clear pipes or other obstructions which might likewise be secured to the joists.

In the use of these hangers, they are hung 65 from the joists at suitable intervals, say ten to twelve feet apart, with their coils 16 disposed at any desired distance from the joists to suit the height most convenient for the user in hanging the clothes. After securing one end of the line to a joist by a nail 70 17 or similar fastening, the remainder of the line is threaded successively through the loops formed by the hanger-legs 14, each section of the line being drawn taut and then 75 anchored to the respective coil 16 by forcing or inserting it between the turns or yieldable jaw portions thereof. The opposite end of the line may then be secured to the adjacent joist in the same manner as that described 80 for its other end. Thus, a plurality of independent line-sections of comparatively short lengths are provided, each section being 85 securely anchored at its ends against slippage, so that the weight of the clothes 90 on each line-section is carried by it alone and is not transmitted to the others, thereby positively avoiding a sagging line and dispensing with the use of clothes line props.

A cellar or other place equipped with 95 these hangers enables a maximum number of clothes to be hung in a limited space, the lines being usually hung in parallel relation so as to leave ample aisle space and provide for air circulation to dry the clothes. While 100 manifestly simple and inexpensive in construction, these improved hangers are strong, durable and neat in appearance, they can be installed quickly and easily, and they enable the clothes lines to be firmly anchored 105 thereto without the use of knots and to always assume a taut, non-sagging position where they do not interfere with the limited head room usually available in attics, cellars and like places.

I claim as my invention:—

1. A clothes line hanger, comprising a single length of resilient wire of substantially U-shape, the looped portion of the hanger being shaped to provide yieldable 110

jaws for pinching the clothes line between them, and the side portions of the hanger terminating in laterally-bent anchoring prongs.

5. 2. A clothes line hanger, comprising a single length of resilient wire of substantially U-shape, the looped portion of the

hanger being shaped into a spiral wound coil of one or more turns, the latter forming yieldable jaws for gripping a clothes line therebetween, and the side portions of the hanger terminating at their free ends in laterally-bent anchoring prongs.

EDWIN J. OYEN.
